FOLDING FURNITURE

Edwin Vanderminden, Granville, N. Y.

Application October 14, 1933, Serial No. 693,539

1 Claim. (CL. 155—117)

This invention relates to folding chairs and especially to means for preventing such chairs from being unfolded in the wrong direction.

Such chairs comprise a plurality of oppositely disposed crossed members which are pivotally secured together in a manner that permits them to be folded into a compact unit. Heretofore, when unfolding such chairs considerable difficulty has been experienced to insure that the various crossed members rotate about their respective pivot pins in the proper direction.

Accordingly, an object of the present invention is to provide means for preventing the various crossed members in structures of this sort from being rotated about their respective pivot pins in the wrong direction and to this end certain of the crossed members are provided with stops which engage other members in the event an attempt is made to unfold such structures in the wrong direction.

For a clearer understanding of the invention reference may be made to the accompanying drawing. In the drawing, however, the invention is merely shown in preferred form and by way of example but obviously many changes and variations may be made therein and in its mode of application which will be comprised within its spirit. It should, therefore, be understood that the invention is not limited to any specific form or embodiment, except in so far as such limitations are specified in the claim.

Referring to the drawing:

Figure 1 is a perspective view of a folding chair embodying the features of the present invention;

Figure 2 is a rear view of one side of a chair partially folded; and

Figure 3 is a detail view, in section, the view being taken along the line 3—3 of Figure 2.

As shown, two oppositely disposed legs 10 and 11 are connected together at their opposite ends in spaced relation by spacers 12 and 13 to form a back supporting frame. Two oppositely disposed legs 14 and 15 cross the legs 10 and 11 and are pivotally secured thereto by pivot pins 16 and 17 respectively and are connected together at their opposite ends in spaced relation by spacers 18 and 19 to form a seat supporting frame. A flexible rest member 20 such as a strip of canvas or other suitable woven material, is secured at one end to spacer 12 and at the other end to spacer 18. Two oppositely disposed struts 21 and 22 are pivotally secured at their upper ends to the seat supporting legs 14 and 15 by pivot pins 23 and 24 respectively. The lower ends of the struts 21 and

22 are connected together in spaced relation by a spacer 25, the spacer 25 being adapted and arranged to be retained in a set of a plurality of sets of oppositely disposed grooves 26 in the rear or lower portions of the seat supporting legs 14 and 15. The height of the chair may be adjusted by varying the position of the spacer 25 in the oppositely disposed grooves 26. Two oppositely disposed arm rests 27 and 28 are pivotally secured at their inner ends to the struts 21 and 22 by pivot pins 29 and 30 respectively. The outer ends of the arm rests 27 and 28 are pivotally secured to the upper ends of arm rest supports 31 and 32 by pivot pins 33 and 34 respectively. The lower ends of the arm rest supports are pivoted to legs 15 and 11 by pivot pins 35 and 36 respectively. To prevent the chair from being unfolded in the wrong direction the arm rest supports are provided with stop members. The stop members desirably employed comprises extensions of the pivot pins 35 and 36 which are adapted and arranged to engage the arm rests 27 and 28 respectively in the event an attempt is made to unfold the chair in the wrong direction. To prevent these pivot pins from remaining exposed when the chair is folded the arm rests 27 and 28 are provided with grooves 37 in which the pins fit.

When the chair is unfolded it is in the position shown in Figure 1. To fold the chair the spacer 25 is removed from the oppositely disposed grooves 26. The crossed seat supporting legs and back supporting legs are then pivoted about their pivot pins 16 and 17 until they are in alignment. The struts 21 and 22 are then swung upwardly about their pivot pins 23 and 24 until they are in alignment with the legs. As the struts are swung upwardly the inner ends of the arm rests 27 and 28 are carried upwardly and inwardly about their pivot pins 29 and 30 respectively and the outer ends thereof are carried downwardly and inwardly about their pivot pins 33 and 34 respectively. Simultaneously, the upper ends of the arm rest supports are carried backwardly about the pivot pins 35 and 36 respectively until the arm rests and the arm rest supports are in alignment at which time the extensions of the pivot pins 35 and 36 are disposed in the grooves 37. Under such conditions, further movement of the struts 21 and 22 about their pivot pins 23 and 24 in a counter clockwise direction as viewed in Figure 1 is prevented by the extensions of the pivot pins 35 and 36. Movement in a clockwise direction, however, which in the present case is the desired direction, is permitted.

While the pins are shown and described as being carried by the arm rest supports 31 and 32, it is obvious that the same result would be obtained by pins secured to the back supporting legs 10 and 11 in position to engage the arm rests 27 and 28 when the chair is folded. Likewise, it is evident that the stop pins may be carried by the arm rests 27 and 28 in which case, they would engage either the arm rest supports 31 and 32 or 10 the back supporting legs 10 and 11 as desired.

Having thus described my invention, I claim:

A chair of the class described comprising two back supporting legs connected together in spaced relation, two seat supporting legs connected together in spaced relation, said back supporting legs and said seat supporting legs being pivotally connected together between their ends, two oppositely disposed struts pivotally connected at

their upper ends to the back supporting legs and connected together at their lower ends by a spacer, a plurality of oppositely disposed grooves in said seat supporting legs adapted to engage said spacer, two oppositely disposed arm rests pivotally connected at their inner ends to said struts, two oppositely disposed arm rest supports, pins for pivotally connecting the upper ends of said arm rest supports to said arm rests, and pins for pivotally connecting the lower ends of said arm rest supports to said seat supporting legs, said arm rests being recessed and said pins which connect the arm rest supports to the seat supporting legs being extended outwardly to engage said recesses to form interengaging stops when the 15 chair is folded.

EDWIN VANDERMINDEN.
